UNITED STATES PATENT OFFICE.

PETER JARDINE, OF HESPELER, ONTARIO, CANADA, ASSIGNOR TO A. E. JARDINE AND COMPANY, LIMITED, OF HESPELER, ONTARIO, CANADA.

PRESS.

Application filed June 1, 1922. Serial No. 565,264.

To all whom it may concern:

Be it known that I, PETER JARDINE, a subject of the King of Great Britain, residing in Hespeler, in the county of Waterloo, 5 Province of Ontario, Canada, have invented certain new and useful Improvements in Presses, of which the following is a specification.

My invention relates to improvements in 10 presses, and relates more particularly to that type of press used for various purposes in machine shops and similar places, and one of the objects of my invention is to rapidly relieve the pressure of the ratchet-hand 15 wheel against the screw, so that the said wheel may be then readily turned by hand to elevate or lower the screw. Another object of my invention is to provide counterbalanced means to remove certain actuating 20 means for the ratchet-hand wheel out of the path of movement of this wheel at certain times, and in the following specification I shall describe mechanical embodiments of means within my invention to effect the objects in view, and what I claim as new will 25 be set forth in the claims forming part of this specification.

Fig. 1 is a side elevation of my improved press. Fig. 2 is a plan view of the operating 30 parts. Fig. 3 is a vertical cross-section on the line 3—3, Fig. 2. Fig. 4 is an end elevation of the parts shown in Fig. 2. Fig. 5 is a perspective view of the means used to apply power to the ratchet-hand wheel. 35 Fig. 6 is a vertical cross-section on the line 6—6, Fig. 5. Fig. 7 is a plan view of the housing used. Fig. 8 is a vertical longitudinal section on the line 8—8, Fig. 7. Fig. 9 is a plan view of the lower thrust block. Fig. 40 10 is a cross-section on the line 10—10, Fig. 9. Fig. 11 is a perspective view of the upper thrust block. Fig. 12 is a plan view of a supporting clamp for the ratchet-hand wheel, and Fig. 13 is a side elevation of this 45 clamp.

In the drawings, like characters of reference refer to the same parts.

In machines of the character under consideration with which I am acquainted, the 50 screw can be readily lowered to obtain the required pressure, but no means is provided to relieve the pressure between the operating wheel and the screw in such manner that this wheel may be readily turned by hand 55 to elevate the screw, and the consequence is

that considerable power is required to raise the screw through the medium of said wheel, with the result that this operation requires more time to perform than is really necessary, and I have designed my machine to 60 overcome this disadvantage.

A is any suitable frame for the machine, and supported between the horizontal members B thereof, by any suitable means such as screws C is the head-block D. This head-block preferably extends below the horizontal members B, and is provided with a bore E throughout its length, through which operates the screw F. This screw is held from turning within the head-block D by any 70 suitable means, such as a key G held in the lower end of this head-block in any suitable manner, and this key extends into a keyway H longitudinally formed in one side of said screw. I is a housing resting against 75 the underside of the head-block D and chambered as shown at J, through which chamber or passageway passes the screw F. K is a ratchet-hand wheel the hub L of which is internally threaded to engage with the 80 threads of the screw F. This ratchet-hand wheel K is located underneath the housing I, and as the bore E is not threaded, some 85 means must be provided to operatively hold the screw and wheel K in relationship to the parts just described; a convenient means for this purpose is in the form of a two-part bore-provided clamp 2 provided with an internal annular flange 3, which flange engages in an annular groove 4 formed in the 90 outer side of the hub L. After the parts of said clamp have been positioned, screws 5 are passed through holes 6 therein and through holes 7 formed in the housing I and screwed into the lower portion of the 95 head-block D.

8 is the upper thrust block provided with a passage-way 9 therethrough, of sufficient size to prevent the said block coming in contact with the screw F at any time. This 100 screw passes through the said block, and this block is mounted to operate in the passage-way or chamber J formed in the housing I, and against the underside of the head-block D. The underside of the block 8 is 105 shaped to provide an inclined plane 10, and this inclined plane rests in contact with the inclined plane 11 formed on the upper side of the lower thrust block 12, which is also provided with a passage-way 13 to permit 110

the screw F to pass therethrough, and without contacting with said block. The lower end of the chamber or passage-way J is preferably provided with an annular flange 14 5 thus constricting this passage-way as shown at M, and the lower portion of the thrust block 12 operates within the said flange which flange acts as a vertical guide for said block, and the higher portion of this block 10 of course is located within the chamber or passageway J. Upon referring particularly to Fig. 3 it will be seen that the diameter of the upper end of the hub L is less than the diameter of the constricted passage-way or 15 opening M through the flange 14, and that this upper end of said hub rests in contact with the underside of the thrust block 12. In the position of the parts shown in Fig. 3 pressure is supposed to be exerted by the 20 ratchet-hand wheel K against the screw F by means hereinafter more particularly described, and since this pressure amounts to many tons, sometimes, it is expedient that means be provided to remove this pressure to 25 permit the wheel K to be readily turned by hand so as to elevate the screw F. Now this pressure can only be relieved by allowing movement to occur between the thrust blocks 8 and 12, and by preferred means to 30 be presently described these thrust blocks are unlocked when it is evident that since no pressure will be exerted between the hub L and the block 12, the pressure between the ratchet-hand wheel K and the screw F will 35 be relieved to permit this wheel to the readily moved by hand.

Some form of locking means must be used to hold the blocks 8 and 12 in the position shown in Fig. 3. The preferred form of 40 locking means consists of an arm 15 associated with the block 8 and extending through a slot 16 formed in one end of the housing I. 17 is a clamping lever provided with a bifurcated head 18 which straddles 45 the outer end of the arm 15, and pivoted in place by a pin 19. The inner end of this lever is provided with a cross bar 20 which in the position of the parts shown in Fig. 3 engages with the underside of the arm 15 50 thus arresting the downward movement of the lever 17. The inner ends 21 of the bifurcated head of the lever 17 in contact with one side of the housing H, hold the upper thrust block 8 against movement to 55 the right: obviously since these thrust blocks are constructed, and associated, as described, the locking of the upper thrust block will simultaneously lock the lower thrust block in its lowest position in contact with the hub L. Now by moving the 60 lever 17 upwardly around its pivot 19, the upper thrust block 8 will be unlocked, and by reason of the angular inclination of the inclined planes 10 and 11 to the horizontal, 65 the pressure of the hub L against the under-

side of the block 12 will give the necessary relieving movement to these blocks, with the result before described, that is to say, the upper thrust block 8 will move to the right, and the lower thrust block 12 will move 70 inwardly longitudinally of the screw F, the direction of this latter movement being controlled by the annular flange or guide 14. The angular inclination of the inclined planes 10 and 11 to the horizontal will of 75 course be such as to permit of the said movements required for the said thrust blocks to be automatically effected when they are unlocked.

I shall now describe the means for manually operating the ratchet-hand wheel K to develop power: 22 is the rack slide, conveniently held between the horizontal members B in any suitable manner: for this purpose I preferably provide the upper part of said rack slide with posts 23 which are located between the said members B and held thereto by suitable holding means such as screws 24. Lugs 25 are adapted to rest against the lower flanges 26 of the members B to co-act 80 with the holding means 24 to hold the rack slide 22 from movement. Of course any other convenient construction may be employed to associate said rack slide with the members B. 27 is the rack which operates 85 through slots 28 formed in the ends 29 of the rack slide 22, and preferably integrally formed with said rack is a housing 30 vertically provided with a passage-way 31 therethrough. One side of the upper end of this housing is slotted as shown at 32 to receive 90 a pin 33 carried by the pawl 34 which operates in the passage-way 31. This pin operates longitudinally within the slot 32 to prevent the pawl 34 from having axial movement. The pawl 34 has an easy fit in the 95 passageway 31 so that this pawl may drop to its lowest position by gravity.

Pivoted between the plates 35 (coupling the posts 23 together, and spaced apart, to 100 provide a slot,) by means of the pin 36, is a segment gear 37, the teeth 38 of which co-act with the toothed-portion 39 of the rack 27. Integrally formed with one side of the segment gear 37 is a housing 40, projecting beyond one side thereof, and suitably coupled to one end of this housing is a counter-weight 41. The housing 40 is chambered as shown at 42 to receive one end of the operating lever 43. Upon referring particularly to Figs. 1 and 2, it will be observed that the pawl 34 is located directly above the teeth 44 of the wheel K. Now when the lever 43 is depressed the segment gear 37 is caused to move, and this movement is transmitted to the rack 27 and housing 30 with the result that the lower end of the pawl 34 comes in contact with one of the teeth 44 and so gives the ratchet-hand wheel K movement: this operation is re- 115 120 125 130

peated as often as desired to obtain the pressure required, and each time the lever 43 is raised of course the segment gear 37, and rack 27 and parts carried thereby, are moved 5 into the position shown in Fig. 5 particularly.

Upon referring particularly to Fig. 5 it will be seen that the lower end of the pawl 34 is cut off to provide an inclined face 45, 10 and that when this face comes in contact with the lifter plate 46 secured to one of the ends of the rack slide 22, the pawl is lifted above the top of the teeth 44. When the lever 43 is depressed, the face 15 45 of the said pawl will slide over the end of the lifter plate 46 so that in due course the end of the pawl will be properly positioned to engage one of the teeth 44.

The lever 43 is designed to be removed 20 from the housing 40 after the required pressure has been obtained, and the result is that the counter-weight 41 will automatically shift the segment gear 37 and rack 27, and since the travel of this rack is sufficient to cause the lifter plate to elevate the pawl 34 sufficiently, the end of this pawl will be out of the path of movement of the teeth 44 so as not to interfere with the movement of the wheel K.

30 47 is any suitable support or rest for the work, and the same is carried by the frame A in any well-known manner.

It will be abundantly clear upon referring to Figs. 1 and 2 that the position of 35 the lever 43 and counter-weight 41 is well to the side of the wheel K so that there is no possibility of conflict therewith. Obviously the hand-power operating means for the wheel K may be located at either side 40 of the screw F.

While I have described what I consider to be the best means to effect the movements set forth in the opening part of this specification, it must be understood that I 45 do not confine myself to the construction thereof since the same may be embodied in many other forms without departing from the spirit of my invention.

What I claim is:

50 1. In a machine of the class described in combination, a screw; a ratchet-hand wheel having an internally threaded hub through which said screw passes; suitable supporting means for said screw and wheel, and means against which said hub thrusts in order to lower said screw, and adapted to be moved when required to relieve the pressure between said hub and said screw, for the purpose specified.

60 2. In a machine of the class described in combination, a screw; a ratchet-hand wheel having an internally threaded hub through which said screw passes; a bore-provided head-block through which said screw freely passes, and adapted to prevent rotation of

said screw; a suitable supporting member carrying said head-block; a chambered housing positioned underneath said head-block and through which said screw passes; suitable means adapted to support said 70 screw and wheel, and means located within said housing and apertured to permit said screw to pass therethrough and against which said hub thrusts and adapted to be moved when required to relieve the pressure 75 between said hub and said screw, for the purpose specified.

3. In a machine of the class described in combination, a screw; a ratchet-hand wheel having an internally threaded hub through 80 which said screw passes; a bore-provided head-block through which said screw freely passes, and adapted to prevent rotation of said screw; a suitable support for said head-block; a chambered housing positioned underneath said head-block and through which said screw passes and provided at its lower end with an annular flange; an upper thrust block provided with a passage-way therethrough and mounted in said chambered 85 housing and to operate against the underside of said head-block, and having its lower face formed to provide an inclined plane; a lower thrust block having a passage-way 90 therethrough through which said screw passes and having its upper face formed to provide an inclined plane located in said chambered housing and which rests in contact with the other inclined plane, the said lower thrust block being guided by said 95 annular flange; the inner end of said hub operating in contact with the outer face of said lower thrust block; clamping means adapted to permit of the relative movements of said thrust blocks to relieve the pressure 100 between said hub and screw, and means whereby said wheel and housing are coupled to said head-block.

4. In a machine of the class described in combination, a screw; a ratchet-hand wheel having an internally threaded hub through 110 which said screw passes; suitable supporting means for said screw and wheel; means against which said hub thrusts in order to lower said screw, and adapted to be moved when required to relieve the pressure between said hub and said screw, and counterweighted actuating means adapted to turn said ratchet-hand wheel to develop the required power, as set forth.

5. In a machine of the class described in combination, a screw; a ratchet-hand wheel having an internally threaded hub through 115 which said screw passes; suitable supporting means for said screw and wheel; means against which said hub thrusts in order to lower said screw, and adapted to be moved when required to relieve the pressure between said hub and said screw; a rack slide; a segment gear pivotally associated with 120 125 130

said slide; a toothed rack adapted to have movement in said rack slide and with which said gear is in constant mesh; a housing carried by said rack slide and provided with a longitudinal passage-way therethrough; a pawl mounted to operate in said passage-way, and located to co-act with said ratchet-hand wheel, when said rack is moved by said segment gear in a given direction to move said wheel; means for moving said pawl out of contact with said wheel at certain times, and a counter-weight associated with said segment gear, for the purpose specified.

15 6. In combination suitable supporting means; a ratchet-hand wheel provided with an internally threaded hub; a screw operating through said hub; means associated with said screw and wheel and carried by said

supporting means and adapted to co-act with 20 said wheel in order when required to relieve the pressure between said hub and screw; a rack slide; a segment gear pivotally associated with said slide; a toothed rack adapted to have movement in said rack slide and 25 with which said gear is in constant mesh; a housing carried by said rack slide and provided with a longitudinal passage-way therethrough; a pawl mounted to operate in said 30 passage-way, and located to co-act with said ratchet-hand wheel, when said rack is moved by said segment gear in a given direction to move said wheel; means for moving said pawl out of contact with said wheel at certain times, and a counter-weight associated 35 with said segment gear, for the purpose specified.

PETER JARDINE.
